UNITED STATES PATENT OFFICE.

JOHN GARVIN, OF PHILADELPHIA, PENNSYLVANIA, ASSIGNOR TO WILLIAM H. MYERS, OF SAME PLACE.

ORE CONCENTRATOR AND SEPARATOR.

SPECIFICATION forming part of Letters Patent No. 255,160, dated March 21, 1882.

Application filed September 28, 1880. (No model.)

To all whom it may concern:

Be it known that I, JOHN GARVIN, of Philadelphia, in the county of Philadelphia and State of Pennsylvania, have invented certain new and useful Improvements in Ore Concentrators and Separators, of which improvements the following is an explicit and exact specification, enabling one skilled in the art to make and construct the same.

10 My invention relates to that class of ore concentrators and separators in which the concentration of the ore is effected by distributing the same upon a horizontal or slightly-inclined table, trough, or tray, the separation of the 15 metal-bearing particles from the refuse clay and sand constituting the gang, being effected by means of continuous oscillations imparted mechanically or otherwise to said table, trough, or tray in the presence of water, and discharging the concentrated ore at one extremity and the gang at the other.

Heretofore machines of this character have been oscillated by means of cranks, eccentrics, cams, differential gearing, or the impact of 25 hammers or suspended weights. The use of the crank or eccentric is objectionable for the reason that neither of them imparts a sufficiently sudden or abrupt motion to the table-bed, the forward movement at the beginning 30 of the stroke being extremely slow, increasing gradually till its maximum of speed is reached toward the middle of its course, and diminishing in inverse order to the end. The inertia of the ore is overcome in the first part of 35 the stroke, and the momentum acquired by it during the course of the stroke is also overcome and consumed during the latter part thereof without producing any material change in the relative positions of the particles of the ore 40 among themselves or having caused them to advance along the bed of the table materially in either direction. Besides, the same series of events occurs in the return-stroke as those described in the forward, only in a contrary 45 sense, so that whatever progress in one direction may have been effected in the forward is neutralized in the return-stroke. To remedy this defect the table is generally placed at an inclination, in which case, however, all the materials are discharged at the lower extremity

of the trough, or at least at a point below that of admission; and the process is either imperfect, owing to the excessive pitch imparted to the table, or excessively tedious and prolonged where the table is only slightly inclined. 55

The cam ordinarily employed, although overcoming the above objections to a certain extent, is itself open to the objection of being capable of giving only one series of unchangeable oscillations, and cannot be driven beyond 60 or below a given speed to produce its best results or to work to the greatest advantage. Differential gearing, which has been employed to meet the defects of the cam, like the cam only gives a series of unchangeable and un- 65 changing reciprocations. It is also too gradual in its action, and does not impart the con- 70 nection necessary to separate the different ingre- 75 dients of the ore. The blow delivered by a hammer operated by a trip on a rotating shaft 70 or otherwise and reciprocated by a spring or gravitation errs in a contrary direction, the im- 80 pact being too instantaneous and violent, the greater part of the force of the blow being ab- 85 sorbed by those portions of the table immedi- 90 ately adjacent to the point of contact, greatly to their detriment, thereby adding to the wear and tear of parts and utilizing only a small fraction of the power exerted for the end in view, and being correspondingly slow of opera- 95 tion and expensive.

It has also been the practice heretofore to introduce the ore and the water separately into the hopper, and to cause them to mingle while going through the different stages of the operation. This method is highly objectionable and insufficient, owing to the water not remaining in contact with the ore a long enough time to thoroughly impregnate every particle thereof, as frequently in finely-divided ores air 90 is contained in sufficient quantity and adhering to the particles with sufficient tenacity to form the ore into little balls of unmoistened dust which float off with the water and the gang without coming under the influence of 95 the oscillating trough, thus occasioning seri- 100 ous loss.

I am aware that in order to overcome these objections it has been the practice to mix the ore to be treated in bulk with water in a sepa-

rate machine by hand or otherwise, and supplying the mixture to a hopper upon and forming part of an ore separator or concentrator, said hopper being provided with rotating mechanism at or adjacent to its discharging-orifice for the purpose of facilitating and regularizing the flow of the ore. This plan, besides being complex and necessitating the employment of separate machinery and additional manual help, is also open to the objection that it does not secure the supply of a perfectly homogeneous mixture constantly of the same degree of fluidity, or containing at all times the same percentage of ore, all of which conditions are, however, necessary for securing the perfect operation for this class of separators.

The object of my invention is to provide a concentrator and separator of cheap and durable construction, which will completely obviate waste of valuable ore, which will be readily and easily adjustable in all its parts, so as to be adapted to the separation of all kinds of ores, finely divided or even as coarse as that which requires ten meshes to the inch for its passage; to be capable of running at any speed, and by a peculiar arrangement of parts to obtain at each separate oscillation a series of concussions, each tending in the same direction and co-operating toward the same result—namely, the delivery of the concentrated ore at one extremity of the trough and the gang at the other.

To these ends my improvements consist in the employment of a mixing-pan in combination with a main receiving-hopper, a laterally-oscillated shaker, and a distributing-hopper, said hoppers and shaker being all capable of being shifted longitudinally, so as to deliver on any portion of the tray beneath; an oscillating table or trough with a smooth metallic bottom, adjustable to any reasonable angle of inclination, and preferably suspended to a supporting-frame by means of flexible attachments vertically and horizontally adjustable; the employment of an abutment upon the frame of the machine for maintaining the trough at an angle from the vertical in a direction opposed to that whence the concussion is imparted to it, said abutment serving also to maintain the trough at the same distance from the axis of rotation of the actuating-cam, besides receiving the full force of the recoil of the table as it falls back into its place after each successive impulse of the cam; and an adjustable actuating-cam for vibrating the table, all as hereinafter more fully set forth.

The nature of our improvements and the manner in which they are to be carried out will be understood, reference being made to the accompanying drawings, in which—

Figure 1 is a vertical section on the line xx of Fig. 2. Fig. 2 is a plan view, the mixing-pan and driving-gear of same being removed. Fig. 3 is an enlarged view, in elevation, of the adjustable cam.

A separating table, trough, or tray, A, is suspended by chains, ropes, or other flexible means

of attachment $a' a'$, made fast at their lower extremities to lugs rigidly fastened to the edges of the trough, and at their upper ends to eyebolts $a^2 a^2$, which in turn are secured to the frame B by clamps $b b$, in such manner as to be easily loosened and slid backward or forward along the stringers $B' B'$ of the frame B by merely loosening the nuts $a^3 a^3$, which also serve to adjust the eyebolts $a^2 a^2$ vertically, when it is found desirable, owing to the nature of the ore, or from any other cause, to alter the inclination of the separating-trough. Adjustable stops $c c$, bifurcated at their lower end, are similarly secured to the frame B directly behind the supporting-chains $a' a'$, and serve to shorten or lengthen the swing of said chains or ropes.

An abutment, B^2 , upon the frame receives the shock of the projection A' of the table as it returns at each oscillation and maintains the table in an abnormal position and continually resting against said abutment.

The bottom of the trough is perfectly smooth and free from joints and seams. This is effected by covering it with sheet metal, preferably composed of an alloy of zinc and lead, which is comparatively non-oxidizable. Two strips, $A^3 A^3$, laid angularly upon the bed of the table, form a horizontal converging channel directing the ascending ore first under the water from a rose, F, secured to the main frame B by rods $f f$, and finally to the opening D in the bed of the trough, where the concentrated ore is discharged.

A strip of hard wood or metal, A^4 , at the rear end of the trough A, is so secured as to be readily removed when worn out and another substituted therefor. This strip serves as an anvil to receive the blows of a bolt, H, rounded at its point of percussion, centrally slotted at or about the middle for the reception of a taper key, and having its rear extremity formed into a screw. It is thus rendered adjustable in the direction of its length by means of the tapering key m and tightening-nuts $n n$, said bolt H fitting in jaws or a pocket upon the carrier-disk L, said jaws or pocket being slotted transversely for the passage of the key m and serving as a guide for the bolt H.

The whole combination of the bolt H, key m , nuts $n n$, and disk L forming an adjustable cam whose function is to deliver a sliding blow, as indicated by dotted line $k k$, Fig. 3, of greater or less continuance, as the bolt H is advanced or retracted, thus enabling the striking mechanism to be operated at any desirable rate of speed. The force of the blow increasing with the velocity, the bolt is withdrawn correspondingly; and, *per contra*, when it is judged necessary to run slower, as is the case when the ore to be treated is of a poorer grade, the bolt is advanced. In this manner I maintain complete control over the force of the blows delivered by the cam, and can always so regulate it that no matter what the speed the oscillating trough will always return to the fixed abutment upon the frame B

before the succeeding blow of the cam H. Upon the shaft K a spur-pinion, O, meshes with and is driven by a spur-gear, O', upon the shaft K', actuated externally by a crank or 5 otherwise, as may be deemed most expedient.

A mixing-pan, T, is placed upon the top of the frame B, preferably one of the kind wherein the stirring apparatus can be elevated and depressed, and is set in motion by 10 the shaft K' through the intermediate pulleys, P P', the belt Q, and the bevel-gears U U'. A spout, T', at the bottom of the mixing-pan, provided with a valve, V, regulates the supply of the mixed ore to the receiving-hopper R.

15 A shaking-pan, W, which I call a "spreading-pan," attached by means of links w w to the hopper R, swings freely beneath the same, and is oscillated laterally by a lever, Y, fastened with a set-screw to the journaled stem N, 20 which carries at one of its extremities a lever, Y', engaging in the cam Z upon the shaft K.

The distributing-hopper R' slides upon the raised sides of the separating-trough in such wise as to admit of being shifted toward either 25 extremity of the same. It is secured in place by set-screws at r r. The distributing-hopper R', the spreading-pan W, its actuating-lever Y, and the receiving-hopper R all admit of being shifted together toward either extremity of 30 the trough A, so as to remain superposed one above the other and in the same relative position as shown in the drawings.

The operation of my machine is substantially as follows: The necessary adjustments having 35 previously been made—namely, the proper inclination of the separating-trough, the angle of the supporting chains, and corresponding resistance of the table or trough to the impact of the actuating-cam, and the consequent rapidity of its return to a point of rest, the position of the stops c c, the proper advancement of the cam H, and the position of the distributing-hopper R' upon the edges of the trough—these 40 adjustments once made will remain constant and will not require to be altered so long as a particular grade of ore is being operated on. The ore to be treated, after going through the crushing process, and having been sized in the usual manner, is fed into the mixing-pan T, together with a sufficient supply of water 45 to form a flowing mixture. The machine is then set in motion, and the valve V is opened sufficiently to allow the proper quantity of the mixed ore to fall into the hopper R, whence it passes onto the spreading-pan W, and is 50 spread by the action of the latter uniformly and over the entire width of the distributing-hopper, which in turn delivers it in this state upon the metallic bed a of the trough A. The 55 repeated concussions imparted to the separating-trough in the direction of its length by the blows of the adjustable cam H have the effect, first, of causing the particles which, owing to their metallic nature, are of a greater specific 60 gravity, to work their way through the sand and earthy matter which usually constitutes the bulk of the ore or tailings operated on

down to the bed of the trough, which they no sooner reach than they commence their ascent toward the upper part of the trough, while the 70 gang or lighter part is worked out at the lower end.

The law in obedience to which the inertia of substances of high specific gravity enables them to overcome gravity in the manner described above to a greater extent than substances of a lighter character is old and well understood, nor need it be detailed at greater length here. It will suffice to state that experience has shown me that an angle of inclination of about one vertical to thirty-six horizontal given to my trough meets the requirements of the average of ores. The trough should be so set therefore as to allow of adjustment either way from this angle, as the case may require. 85

I have also found that a metallic bottom, owing to its smoothness, offers less frictional resistance to the movements of the ore, thus greatly assisting in the operation and permitting of the running of the machine at a higher 90 speed. Such a metallic bed prevents the access of water to the wooden body of the trough, which will therefore not be liable to swell when wet and contract when dry, and hence is always ready for use, which is not the case with 95 troughs not similarly protected.

As the ore passes up above the point of delivery upon the trough it gets more and more concentrated, and as this concentration depends in a great measure upon the distance which 100 the ore has to travel before reaching the outlet, I have so arranged the lower hopper, R', that it may be placed to deliver farther up or down upon the trough as the ore is richer or poorer respectively. As the ore continues to 105 ascend the oscillating trough it eventually reaches a point where the angularly-disposed strips converging from the sides toward the center guide it first beneath a rose supplied with water under pressure, which frees it from 110 any such clayey or foreign matter as may have found its way up, in defiance of all other precautions, and, finally, to the opening of discharge, whence it falls into a receptacle provided therefor. 115

It will be seen from the construction of my improvements that while of very cheap manufacture, all the working parts are adjustable to each other and to the particular variety or grade of ore to be treated. I can work to advantage, at one operation, ores that have been sized through screens or sieves of a difference of twenty meshes to the inch—thus all between ten to thirty, twenty to forty, thirty to fifty, &c., meshes to the inch; but in practice I prefer to 120 work simultaneously and at the same operation ores not differing more than ten meshes—thus ten to twenty, twenty to thirty, &c. 125

By the peculiar distribution of the cam, the adjustable stopping-rods, and the abutment, 130 I am enabled to obtain three distinct concussions at each revolution of the cam, the tendency of which is all in the same direction, to wit: first, the reaction due to the impact of the

cam; second, the acceleration of said reaction occasioned by the shortening of the pendulums supporting the trough; and, third, the impulse conveyed to the ore in the same direction by the momentum acquired in the return-swing of the trough, which is continued with the ore after the trough has been suddenly checked by the abutment.

I claim as my invention and desire to secure

by Letters Patent—

1. In an ore concentrator and separator, the combination of a laterally and horizontally oscillated spreading-pan, a sliding distributing hopper, and a longitudinally-oscillating trough,

15. 2. In an ore concentrator and separator, the combination of a mixing-trough, a receiving hopper, a horizontally and laterally oscillated spreading-pan, a distributing sliding hopper, and an oscillating trough or tray, substantially as described.

3. The combination, with an oscillating trough or tray, of hanging and swinging flexible supports adjustable vertically and horizontally, substantially as set forth. 25

4. The combination, in an ore concentrator and separator, of an oscillating trough or tray provided with horizontally-adjustable supports, of an abutment and an adjustable cam, substantially as set forth. 30

5. The combination, in an ore separator, of an oscillating trough or tray provided with hanging and swinging flexible supports, and of stops adjustable vertically and horizontally, substantially as described.

JOHN GARVIN.
